UNITED STATES PATENT OFFICE.

FREDERICK DIETRICH, OF FLUSHING, NEW YORK, ASSIGNOR TO C. BRANDES, INC.,
OF NEW YORK, N. Y., A CORPORATION OF NEW YORK.

ELECTRICAL CONNECTION FOR TELEPHONE HEADSETS.

Application filed November 5, 1923. Serial No. 672,949.

To all whom it may concern:

Be it known that I, FREDERICK DIETRICH, a citizen of the United States, residing at Flushing, in the county of Queens and State of New York, have invented a certain new and useful Improvement in Electrical Connections for Telephone Headsets, of which the following is a specification.

My invention relates broadly to telephone headsets, and more particularly to an arrangement of connections between the telephone receiver and the conductors connecting the telephone receiver with the electrical circuit in which it is associated.

One of the objects of my invention is to provide a telephone headset construction in which the electrical connections with the telephone receivers are made without removing the caps and diaphragms from the telephone cups or casings.

Another object of the invention is to provide a telephone headset in which the conductors which electrically connect the telephones in the associated circuit are electrically shielded with a connection between the shield and the telephone cups or casings, the connection being so arranged with respect to the other conductors that it serves as a means for removing the strain from the other conductors in addition to its function as an electrically connecting member.

Another object of the invention is to provide a simplified construction of terminal block for a telephone receiver arranged to be secured in relation to the electro-magnetic operating system in the receiver in such manner that electrical connections may be made without removing the cap and diaphragm from the telephone receiver.

Another object of the invention is to provide a terminal block for a telephone head receiver in which all live parts are not liable to contact by the user, at the same time that the conducting cord may be attached without removing the cap and diaphragm and thereby preserving the delicate factory adjustment initially given the receiver.

Still another object of the invention is to provide flat connecting members as terminals for the telephone connecting cords arranged to cooperate with the clamping device within the telephone receiver casing operative from the exterior of the casing to clamp the flat terminal members rigidly be-

tween flat surfaces with all live parts well insulated.

Other and further objects of my invention will be pointed out in the following specification by reference to the accompanying drawings, in which:

Fig. 1 is a perspective view of my telephone headset showing the arrangement of the connecting member which serves both to relieve the strain from the telephone conductors and electrically connect the electrostatic shield which encases the conductors with the telephone cups or casings; Fig. 2 is a rear plan view of one of the telephone receivers employed in the headset showing the arrangement of the telephone conductors and the electrostatic shield connector and strain relieving member; Fig. 3 is a front plan view of one of the telephone receivers with the telephone cap and diaphragm removed, illustrating the clamping device interior of the telephone receiver casing which is operated from the exterior of the casing for clamping the telephone leads in the casing without removing the telephone cap or diaphragm from the receiver casing; Fig. 4 is a cross-sectional view of the telephone receiver taken on line 4-4 of Fig. 3; Fig. 5 is a plan view showing one arrangement of the terminals for the telephone cords with the strain relieving member and electrical connector for the electrostatic shield and the telephone receiver casing disposed intermediate the telephone conductors; Fig. 6 is a side view showing the flat construction of the terminals for the telephone conductors; Fig. 7 is an end view of one of the flat terminals; Fig. 8 is a fragmentary perspective view of the telephone conductors disposed in the electrostatic shield; and Fig. 9 illustrates the application of my headset to sensitive electron tube amplifiers for use in line wire or radio receiving systems.

My telephone headset is provided with an electrostatic shield which is the subject matter of an application for patent filed by Wendell L. Carlson and Glenn W. Carpenter on January 29, 1921, Serial Number 440,992 on telephone receivers for radio telephony and other uses.

My present invention practically applies the principle set forth in the above entitled application to radio headsets. I provide a flexible connecting cord for the telephone

receivers of the headset with tips on the extremities of the telephone cords and on the connector which extends from the electrostatic shield surrounding the telephone cords. At the points the cords enter the telephone receiver casings I provide a short connector intermediate the pair of connectors which connect with the telephone cords. This short intermediate connector is electrically connected with the electrostatic shield surrounding the telephone conductors, and by reason of its short length with reference to the adjacent pair of connectors it serves to remove the mechanical strain imposed upon the connectors by constant pulling of the telephone cords. The three connectors are provided with flat strip-like terminals. The interior of the telephone receiver casing is provided with flat terminal lugs and a flat contact grounded to the cup of the telephone receiver. A clamping block is arranged over the terminal lugs and ground contact in such manner that the terminals on the telephone conductors, which may be either round or flat, may be rigidly secured against the terminal lugs and ground contact within the telephone receiver by movement of the clamping block from the exterior of the telephone receiver. I have discovered that if it becomes necessary to remove the cap and diaphragm of a telephone receiver to attach a new cord, after it has been once adjusted and passed factory inspection, that the adjustment is in many cases destroyed or at least greatly modified. Heretofore it has been necessary to remove the caps and diaphragms from the telephones when the cord terminals are to be removed or inserted by means operative on the interior of the receiver casing. Under such circumstances it is impracticable to expect permanent operation of the telephone receivers, and repairs and readjustments of the telephones must be anticipated. By my present arrangement of terminal clamping means operative from the outside of the telephone receiver it is unnecessary to remove the caps from the telephones after initial setting, and in this way the receivers may be permanently adjusted. Therefore, the caps on the receivers are secured upon the casings with relatively great force inasmuch as there is no occasion for the removal thereof.

In Fig. 1, I have shown the telephones 1 and 2 supported in yokes 3 and 4 respectively, carried by seamless fabric webbing headband 5 as more fully described in my Patent No. 1,447,969 granted March 13, 1923. The telephone conductors are carried in flexible cable 6 shown more clearly in Fig. 8. The cable includes conductors 7 and 8 each being substantially insulated and provided at their extremities with tips 9 and 10 respectively. An electrostatic shield 11 is provided which substantially encases the con-

ductors 7 and 8 throughout the length thereof and which terminates in a flexible lead 12 substantially longer in length than the telephone conductors 7 and 8. A tip 14 is provided on the extremity of the electrostatic shield connector 12. At the point where the telephone conductors enter the telephone receiver casings 1 and 2 the leads are fanned out as represented at 15, 16 and 17, and 18, 19 and 20. The electrostatic shield leads 16 and 19 are short as compared with the telephone conductors 15—15 and 18—20 respectively. The telephone conductors are shown containing a substantial amount of play while the electrostatic shield leads 16 and 19 are shown as taut and subject to a mechanical strain which might be imposed upon the telephone cords. The tips of the leads 15, 16 and 17, and 18, 19 and 20 are formed of flat strip members as represented in Figs. 5, 6 and 7. The connectors 15, 16 and 17 terminate in flat strip members 21, 22 and 23. Each flat strip member is provided with an upturned or substantially hook shaped end 24. The telephone receiver casing 1 includes an electromagnetic operating mechanism comprising electromagnets 25 and permanent magnets 25. A substantially semi-circular terminal block 26 is positioned in the casing and maintained relative to permanent magnets 25 by members 26^a and 26^b. The terminal block includes a chordal portion 27 which contains a rectangular recess 28. Terminal lugs 29 and 30 are provided in opposite ends of the rectangular recess 28, each of which present flat surfaces 31 and 32 respectively in the plane of the terminal block 27. A flat ground contact 33 is disposed between the terminal lugs 31 and 32 and connected with the metallic casing 1. All live parts are well insulated and concealed, preventing accidental touching by the user. A pair of adjusting screws 34 are passed through the terminal block 26 from the exterior of the casing 1 and carry the insulated clamping block 35. The clamping block 35 contains three protruding faces 36, 37 and 38 which abut against the flat surfaces of terminals 23, 22 and 21 respectively when the terminals are inserted through the telephone receiver casing 1, clamping the terminals firmly in electrical contact with lug 31, ground contact 33, and lug 32 respectively. The hook shaped ends 24 on the flat strip-like terminals serve to firmly anchor the connectors in the receiver by drawing clamping block 35 against the flat terminals by operation of screws 34, the hook portions protruding slightly beyond the side of the clamping block.

My headset is particularly adapted for operation with sensitive mult stage electron tube amplifiers. In Fig. 9 I have represented the application of the invention to a radio receiving system. An antenna system

39 has been diagrammatically illustrated with a receiving circuit 40 coupled thereto. Two stages of radio frequency amplification 41 and 42 are illustrated in association with detector 43 and two stages of audio frequency amplification 44 and 45. The connector 12 which connects with the electrostatic shield 11 is shown connected with the low potential filament circuit 46 of the amplifier. It will be understood that the electrostatic shield 11 extends throughout the length of the telephone conductors, eliminating the electrostatic feedback of energy from the telephone circuit to any of the input circuits with the inherent howling and distortion of the received signals.

From the foregoing description it will be understood that the electrostatic shield connector operates to relieve mechanical strain on the telephone cords at the same time that it provides an electrical connection between the shield and the telephone receiver casings. By loosening screw members 34 the flat strip-like terminals may be slipped 25 into the telephone receiver casing from the exterior and rigidly clamped to the terminal block without removing the caps or diaphragms from the telephone receivers once they have been matched in tone and passed 30 all tests imposed by factory inspection.

While I have described my invention in association with flat terminal members on the telephone conductors, it will be understood that round terminals may also be used. 35 It will also be understood that the concealed clamping arrangement may be used with or without the electrostatic shield connector, and that other modifications may be made, and no limitations other than are imposed 40 by the scope of the appended claims are intended.

What I claim and desire to secure by Letters Patent of the United States is as follows:

45 1. A telephone headset, comprising in combination a receiver casing including electromagnetic operating means, a single longitudinally extending clamping means interior of said casing operative from the exterior thereof, a plurality of connections adapted to be completed by said clamping means, a plurality of conductors leading through said casing and secured under said single longitudinally extending clamping 50 means, one of said conductors being shorter than the other of said conductors and electrically connected to a shield encasing said other conductors whereby said shorter conductor serves to electrically connect said casing with said shield and removes the strain from the other conductors.

55 2. A telephone headset, comprising in combination a receiver casing, an electromagnetic system carried therein, an insulated member forming a housing for a three

terminal connecting block in said casing, a telephone cord containing a pair of conductors and a metallic shield extending over said conductors, connections extending from said pairs of conductors and from said shield and secured to said terminal block and within said insulated member, the connection from said shield serving to relieve the strain between said pair of conductors and said telephone casing, and electrically 75 connect said shield with said casing.

3. A telephone headset, comprising in combination a receiver casing, an electromagnetic operating system in said casing, a unitary longitudinally extending clamping 80 block in said casing operative from the exterior thereof, a telephone cord comprising a pair of conductors and a shield surrounding the conductors, terminal ends fanned out from said conductors and electrically 85 connected to said terminal block, and strain relieving means positioned between said pair of conductors and serving to electrically connect said shield and said casing.

4. A telephone headset, comprising in combination a receiver casing, an electromagnetic system carried in said casing, a unitary longitudinally extending terminal block having a plurality of connectors thereon, a telephone connecting cord having a 90 pair of conductors with terminals for connection to said connectors on said terminal block, a longitudinally extending clamping means adjacent said terminal block, a flexible metallic casing for electrostatically 100 shielding said telephone cord, a combined strain member and electric conductor secured between said shield and said terminal block, and means exterior of said casing for operating said clamping means over the entire 105 number of said connectors.

5. A telephone headset, comprising in combination a receiver casing including electromagnetic operating means, longitudinally 110 extending clamping means interior of said casing operative from the exterior thereof, a longitudinally extending block adjacent said clamping means, a plurality of flat connectors carried by said block, a pair of conductors leading through said casing and secured to a pair of said flat connectors by operation of said longitudinally extending clamping means, one of said conductors being connected to another of said flat connectors located between said pair of conductors and having a shorter length than said pair of conductors, a shield encasing said pair of conductors and secured to said longitudinally 120 extending clamping means whereby said shorter conductor serves to electrically connect said casing with said shield and remove the strain from said other conductors.

6. Electrical connections for telephone receivers, comprising in combination a telephone receiver casing, electromagnetic op- 125

- erating means therein, a terminal block adjacent said means, a chordal portion on said block, a rectangular slot therein, a pair of lugs in opposite ends of said slot and connected with said electromagnetic operating means, a ground contact intermediate said lugs, telephone cords having terminal connectors on their extremities arranged to enter one side of said casing and contact with 10 said lugs and ground contact, and means in said slot operative from the exterior of said casing for firmly clamping said terminal connectors against said lugs and ground contact.
16. 7. Electrical connections for telephone receivers, comprising in combination a telephone receiver casing, electromagnetic operating means therein, a terminal block adjacent said means, a recess in said block, connections from said electromagnetic means terminating in said recess, a plurality of telephone cords having terminal connectors at their extremities arranged to enter said recess from the exterior of said casing, and 25 means overlying all of said connections in said recess and operative from the exterior of said casing for clamping said terminal connectors and said connections in substantial electrical and mechanical contact.
30. 8. Electrical connections for telephone receivers, comprising in combination a telephone receiver casing, electromagnetic operating means therein, a terminal block adjacent said means, a recess in said block, connections from said electromagnetic means terminating in said recess, a plurality of telephone cords having terminal connectors at their extremities arranged to enter said recess from the exterior of said casing, and 35 means in said recess comprising a block extending over all of said connections in said recess and arranged for longitudinal travel upon a screw operative from the exterior of said casing for clamping said terminal connectors and said connections in substantial 40 electrical and mechanical contact.
45. 9. Electrical connections for telephone receivers, comprising in combination a telephone receiver casing, electromagnetic operating means therein, a terminal block adjacent said means, a recess in said block, lugs in opposite ends of said recess connected with said electromagnetic mechanism, a ground contact in said recess intermediate said lugs, a plurality of telephone conductors each having a terminal for connection with said lugs and ground contact, a block disposed in said recess over said lugs and ground contact, a protruding face on said 50 block adjacent each of said lugs and ground contact and means operative from the exterior of said casing for clamping said terminals between said lugs and ground contact.
60. 10. Electrical connections for telephone receivers, comprising in combination a telephone receiver casing, electromagnetic operating means therein, a terminal block adjacent said means, a recess in said block, a plurality of contacts in said recess one being grounded to the receiver casing and two being connected with said electromagnetic mechanism, a set of three flexible connectors having flat terminal strips at their extremities arranged adjacent said contacts, a clamping block carried in said recess and extending over all of said contacts and screw means passing through said clamping block on either side of said ground contact and operative from the exterior of said casing for clamping said terminals between said 65 block and contacts.
70. 11. Electrical connections for telephone receivers, comprising in combination a receiver casing, an electromagnetic mechanism therein, a plurality of flat contacts in said casing connected to said electromagnetic mechanism, a plurality of telephone conductors arranged to enter said casing, substantially flat terminal members carried thereby and a flat clamping member extending over all of said flat contacts and arranged to clamp said flat terminals firmly against said flat contacts.
75. 12. Electrical connections for telephone receivers, comprising in combination a receiver casing, an electromagnetic mechanism therein, a plurality of flat contacts in said casing connected to said electromagnetic mechanism, a plurality of telephone conductors arranged to enter said casing, a flat terminal member having a substantially hook shaped end carried by each of said conductors and adapted to connect with said flat contacts, a flat clamping block mounted over the flat portions of said terminal member, means for drawing said block firmly against said terminal members with the hook shaped ends of said members extending beyond the edge of said block whereby said cords are rigidly anchored in said telephone receiver casing.
80. 13. A telephone receiver, comprising in combination a casing, electromagnetic means, permanent magnetic means in one portion of said casing, a terminal block in another portion of said casing and having its opposite ends extending toward said permanent magnetic means; and unitary means adjacent each end of said terminal block and permanent magnetic means for securing both said terminal block and said permanent magnetic means in said casing.
85. 14. A telephone receiver, comprising in combination a casing, electromagnetic means, permanent magnetic means in one portion of said casing, a substantially semi-circular terminal block in another portion of said casing having its ends extending to a position adjacent the ends of said permanent magnetic means, and means secured to said 90
95. 15. 16. 17. 18. 19. 20. 21. 22. 23. 24. 25. 26. 27. 28. 29. 30. 31. 32. 33. 34. 35. 36. 37. 38. 39. 40. 41. 42. 43. 44. 45. 46. 47. 48. 49. 50. 51. 52. 53. 54. 55. 56. 57. 58. 59. 60. 61. 62. 63. casing overlapping the ends of both said terminal block and said permanent magnetic means for binding said terminal block and said permanent magnetic means in said casing.

15. A terminal block for a telephone receiver having an electromagnetic operating mechanism, comprising an insulated body portion, a recess in said body portion, a plurality of electrical contacts in said recess connected with said electromagnetic operating mechanism and an insulated block arranged to substantially close said recess, a plurality of connecting terminals arranged to extend into said body portion adjacent said contacts, and means for clamping said block against said terminals whereby electrical connection with said electromagnetic operating mechanism is maintained and substantially insulated from objects external to said body portion.

16. A terminal block for a telephone receiver having an electromagnetic operating mechanism, comprising an insulated substantially semi-circular ring shaped body portion, a recess in one face of said body portion, a plurality of contacts in said recess connected with said electromagnetic operating mechanism, an insulated block arranged to substantially close said recess and abut

against said contacts, a plurality of connecting terminals arranged to enter one side of said body portion and abut with said contacts, and means for clamping said block relative to said body portion for maintaining firm electrical connection between said contacts and terminals whereby said body portion is substantially insulated on all sides thereof.

17. A terminal block for a telephone receiver having an electromagnetic operating mechanism, comprising an insulated body portion, a recess in said body portion extending downwardly from the top face thereof, a pair of metallic angular members carried in said body portion at opposite ends of said recess, each of said members extending into said recess, connections between said members adjacent the top face of said body portion and said electromagnetic operating mechanism, an insulated block arranged to substantially close said recess, a set of terminals arranged to enter one side of said body portion and connect with said contacts, and means for drawing said block and body portion together whereby said contacts and terminals are firmly clamped and insulated from objects exterior to said body portion.

FREDERICK DIETRICH.
